UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

BODY AND TRUCK BOLSTER.

No. 825,032.

Specification of Letters Patent.

Patented July 3, 1906.

Application filed August 23, 1905. Serial No. 275,383.

To all whom it may concern:

Be it known that I, ETHAN I. DODDS, a citizen of the United States, residing at Pullman, in the county of Cook and State of Illinois, 5 have invented certain new and useful Improvements in Body and Truck Bolsters, of which the following is a specification.

My present invention pertains to metallic body and truck bolsters for cars and includes angle-bars riveted to the sides of the bolsters to which the top plate is fastened. By varying the position and size of such angle-bars I am enabled to change the depth of the sides of the bolster and the strength of 15 the same.

This invention relates more particularly to the use of such angle-bars in bolsters having their sides integral with the bottom plate at its central portion, the bottom being provided with integral upturned flanges for the remainder of its length to which the side plates are fastened.

In the accompanying drawings, wherein like reference characters refer to like parts throughout, I have illustrated the preferred embodiment of my invention.

Figure 1 is a perspective view of the truck-bolster embodying my invention. Fig. 2 is a central longitudinal vertical section of the 30 coöoperating body and truck bolsters, each embodying my invention. Fig. 3 is an enlarged end view of the two bolsters shown in Fig. 2. Fig. 4 is an enlarged cross-section on the line 4-4 of Fig. 2 looking in the direction 35 of the arrows. Fig. 5 shows the blank from which the body-bolster is made, and Fig. 6 is a similar blank from which the truck-bolster is constructed.

Referring first to Fig. 5, the method of 40 manufacturing the body-bolster will be set forth in detail, and it will be evident from this description how the truck-bolster is made from the blank shown in Fig. 6, since the operations are in all respects similar. A rectangular sheet of metal 10 is sheared at each end with two bent cuts on the lines 11 12 13. The sheet is then cut at each end on two parallel lines 14 15, thereby removing from the sheet the tapered pieces of metal, leaving 45 recesses of the shape shown in Fig. 5. In order to provide means to unite the bottom of the bolster with the sides, I bend up four flanges 16 on the lines 17, the flanges being integral with the central strip of the plate which is to

form the bottom of the bolster when bent to 55 shape. The sides 18 are then folded up on the parallel lines 19, joining the points 13, until they are at right angles with the central portion of the bottom 20. The central strip of the plate is then bent on the lines 21 to 60 form the inclined portions of the bottom 22 and is also bent on the lines 23 to form the horizontal portions of the bottom 24, flanges 16 extending between and overlapping the lower edges of the sides 18, to which they are 65 riveted. The main portion of the truck-bolster is constructed similarly from the blank shown in Fig. 6. After the body-bolster has been bent to shape angle-bars 25 are riveted to the sides adjacent to their upper edges 70 with the flanges of the angle-bars extended outwardly, as shown in Fig. 3. To these flanges I rivet a top tension-plate 26. I provide dish-shaped members 27 to space apart the sides of the bolster and at the same time 75 join them together, the members being fastened to the sides by rivets, which pass also through flanges 16 and angle-bars 25. After the main portion of the truck-bolster has been bent to shape, as described above, I 80 rivet adjacent to its upper edges angle-bars 25', which are similar to the angle-bars 25 of the body-bolster; but in the truck-bolster they extend over only a portion of the length 85 of the bolster, whereas in the body-bolster they extend substantially the full length of the structure. To the angle-bars 25' I rivet a top compression-plate 26'. Dish-shaped members 27' are provided for the truck-bolster and perform the same function therefor that 90 the members 27 do for the body-bolster. The rivets which hold the members 27' in place pass through the flanges 16', the sides of the bolster 18', and the side guide-plates 28.

It will be apparent that by using blanks, 95 as shown in Figs. 5 and 6, of a standard size I may vary the strength and size of the finished bolster by employing larger or smaller angle-bars at the top edges or by allowing the angle-bars to extend more or less above 100 the upper edges of the side plates.

It will be understood that the details of construction may be somewhat modified without departing from the spirit of the invention, and accordingly I do not limit myself to the exact details shown and described, except to the extent that they are made the subject-matter of specific claims.

This patent is intended to embrace only so much of the disclosure made herein as is covered by the claims.

I claim—

- 5 1. A car-bolster having side plates, a bottom plate integral with said side plates for a portion of its length, said bottom plate also having flanges riveted to said side plates, and an angle-bar riveted to each of said side plates adjacent to its upper edge, substantially as described.
- 10 2. A car-bolster having side plates, a bottom plate integral with said side plates for a portion of its length, said bottom plate also having flanges riveted to said side plates, an angle-bar riveted to each of said side plates adjacent to its upper edge, and a top plate riveted to said angle-bars, substantially as described.
- 15 3. A car-bolster having side plates, a bottom plate integral with said side plates for a portion of its length, said bottom plate also having integral flanges riveted to said side plates, and an angle-bar riveted to each of said side plates adjacent to its upper edge, substantially as described.
- 20 4. A car-bolster having side plates, a bottom plate integral with said side plates for a portion of its length, said bottom plate also having integral flanges riveted to said side plates, an angle-bar riveted to each of said side plates adjacent to its upper edge, and a top plate riveted to said angle-bars, substantially as described.
- 25 5. A car-bolster having side plates, a bottom plate integral with said side plates for a portion of its length, said bottom plate also having flanges riveted to said side plates, and an angle-bar with an outwardly-extended flange riveted to each of said side plates adjacent to its upper edge, substantially as described.
- 30 6. A car-bolster having side plates, a bottom plate integral with said side plates for a portion of its length, said bottom plate also having flanges riveted to said side plates, and an angle-bar with an outwardly-extended flange riveted to each of said side plates adjacent to its upper edge, substantially as described.
- 35 7. A car-bolster having side plates, a bottom plate integral with said side plates for a portion of its length, said bottom plate also having integral flanges overlapping and riveted to said side plates, and an angle-bar with an outwardly-extended flange riveted to each of said side plates, substantially as described.
- 40 8. A car-bolster having bellied side plates, a bottom plate integral with said side plates for a portion of its length, said bottom plate also having integral flanges overlapping and riveted to said side plates, and an angle-bar with an outwardly-extended flange riveted to the outer side of each side plate adjacent to its upper edge, and a top plate riveted to the outwardly-extended flanges of said angle-bars, substantially as described.
- 45 9. A car-bolster having bellied side plates, a bottom plate integral with said side plates for a portion of its length, said bottom plate also having flanges riveted to said side plates, an angle-bar with an outwardly-extended flange riveted to each of said side plates adjacent to its upper edge, substantially as described.
- 50 10. A car-bolster having bellied side plates, a bottom plate integral with said side plates for a portion of its length, said bottom plate also having flanges riveted to said side plates, an angle-bar with an outwardly-extended flange riveted to each of said side plates, substantially as described.

its upper edge, and a top plate riveted to said outwardly-extended flanges of said angle-bars, substantially as described.

7. A car-bolster having side plates, a bottom plate integral with said side plates for a portion of its length, said bottom plate also having integral flanges riveted to said side plates, and an angle-bar with an outwardly-extended flange riveted to each of said side plates adjacent to its upper edge, substantially as described.

8. A car-bolster having side plates, a bottom plate integral with said side plates for a portion of its length, said bottom plate also having integral flanges riveted to said side plates, an angle-bar with an outwardly-extended flange riveted to each of said side plates adjacent to its upper edge, and a top plate riveted to the outwardly-extended flanges of said angle-bars, substantially as described.

9. A car-bolster having bellied side plates, a bottom plate integral with said side plates for a portion of its length, said bottom plate also having integral flanges overlapping and riveted to said side plates, and an angle-bar with an outwardly-extended flange riveted to each of said side plates, substantially as described.

10. A car-bolster having bellied side plates, a bottom plate integral with said side plates for a portion of its length, said bottom plate also having integral flanges overlapping and riveted to said side plates, and an angle-bar with an outwardly-extended flange riveted to the outer side of each side plate adjacent to its upper edge, and a top plate riveted to the outwardly-extended flanges of said angle-bars, substantially as described.

In testimony that I claim the foregoing as my invention I have hereunto signed my name in the presence of two witnesses.

Chicago, Illinois, August 19, 1905.
